DESIGN FOR A COMBINED BOTTLE OPENER AND KEY RING

Myron H. Pietrzyk, San Francisco, Calif.

Application March 10, 1941, Serial No. 99,484

Term of patent 14 years

To all whom it may concern:

Be it known that I, Myron H. Pietrzyk, a citizen of the United States, residing at San Francisco, in the county of San Francisco and State of California, have invented a new, original, and ornamental Design for a Combined Bottle Opener and Key Ring, of which the following is a specification, reference being had to the accompanying drawing, forming part thereof.

Figure 1 is an elevational view of a combined

bottle opener and key ring showing my new design.

Figure 2 is a bottom plan view thereof.

Figure 3 is an edge elevational view thereof, and taken at right angles to Figure 1.

I claim:

The ornamental design for a combined bottle opener and key ring, as shown.

MYRON H. PIETRZYK.
